CLAIM

The ornamental design for a portable rechargeable light, as shown and described.

DESCRIPTION

FIG. 1 is a side elevational view of the novel portable rechargeable light of the present invention, the other side being identical;

FIG. 2 is an end elevational view of the portable rechargeable light of the present invention, the other end being identical;

FIG. 3 is a top plan view of the portable rechargeable light of the present invention;

FIG. 4 is a bottom plan of the portable rechargeable light of the present invention;

FIG. 5 is an isometric view of the side and end of the portable rechargeable light of the present invention; and,
FIG. 6 is an isometric view of the bottom and end of the portable rechargeable light of the present invention.
